UNITED STATES PATENT OFFICE

HERMAN REICH, OF DES MOINES, IOWA

STAPLE PULLER

Application filed April 16, 1928. Serial No. 270,330.

This invention relates to staple pullers of that class especially designed for use in connection with the removal of wire fences in which the wires are held to upright posts by staples.

The object of my invention is to provide a staple puller of this class in which the sharpened point of the staple puller may be readily, quickly and easily driven into the post in which the staple is embedded, and during said driving movement the sharpened end may be easily held in proper position for entering the post so that the flattened upper surface of the end of the staple puller 10 may engage the fence wire at the point where the staple crosses the fence wire, and so that said point, while being driven may be easily held by the operator against twisting or turning movements such as might be caused by 15 the grain of the wood into which the staple is driven, and whereby when the staple puller has been driven to the proper point, the operator may by utilizing the puller handle as a fulcrum readily and easily withdraw the 20 staple from the wood.

Also to provide a tool of this class in which the staple may be pulled just as readily from a point in the post adjacent to the ground surface as it can from any other point.

30 My invention consists in the construction of the staple puller, whereby the objects contemplated are attained, as hereinafter more fully set forth, pointed out in my claim, and illustrated in the accompanying drawings, in 35 which:

Figure 1 shows a top or plan view of a staple puller embodying my invention.

Figure 2 shows a side elevation of same.

40 Figure 3 shows a transverse sectional view on the line 3—3 of Figure 1.

Figure 4 shows a transverse sectional view on the line 4—4 of Figure 1.

45 Figure 5 shows a side elevation of the lower portion of the fence post with a fence wire adjacent thereto and a staple driven into the post and across the wire, and with my improved staple puller having its point inserted into the post at the proper point to be driven 50 under the wire and staple.

Figure 6 shows a horizontal sectional view on the line 6—6 of Figure 5; and

Figure 7 shows a similar view with the staple puller driven into the post to such an extent as to partly move the staple outwardly.

Referring to the accompanying drawings, my improved staple puller comprises a handle or body portion 10. This handle or body portion is made relatively flat on its top and bottom and of greater width than its thickness, so that when held in the operator's hand it can be held against twisting or turning movements as distinguished from articles of this kind having round or nearly round handles which cannot be conveniently held against twisting movements.

At one end of the handle there is a tapered point indicated generally by the numeral 11 and this tapered point is projected relative to the handle at an angle of about 32°. Its top surface is made flat for the purposes hereinafter made clear, and its under surface is also made flat transversely, but the bottom surface tapers toward the top surface to a point near the end of the tool where it is rounded at 12.

As will be seen in Figures 3 and 7, the tool point tapers from a maximum width at the bottom to a somewhat less width at the top, but both the bottom and top are flat.

In the drawings the reference numeral 13 is used to indicate a staple of ordinary construction driven into a post 14 to hold a wire 15, and when the staple is thus driven into the post ordinarily the wire becomes kinked, as shown at 16 in Figure 6.

Assuming that it is desired to remove a fence wire from a post, and that this fence wire is near the bottom of the post, then the operator places the tool in the position shown in Figure 5, with the pointed end resting against the wooden post, with the under surface of the tool point adjacent to the post at an angle nearly approaching the vertical, so that the handle end extends outwardly and upwardly away from the post. The tool is then tilted laterally at an angle of about 45° relative to the outer end of the staple. Then the operator strikes a hammer blow upon the handle end of the tool and thus forces

the pointed end into the wood of the post to about the position shown in Figure 6. That is to say, with the upper face of the pointed end in engagement with the kinked portion 5 16 of the wire 15, and in such position that when the point is further driven it will pass diagonally through between the ends of the staple. Then the tool is struck repeatedly with a hammer and the pointed end is driven 10 to the position shown in Figure 7. During this operation the broad flat under surface of the pointed end is in engagement with the post and will penetrate it only to a slight degree. The flat upper outer surface of the 15 pointed end will draw the staple away from the post.

In this connection it should be explained that when the staples are driven into the hard wood, the staple adheres so firmly to 20 the post that if an irregular or rounded surface of the tool engaged the fence wire immediately under the end of the staple, it will require so much force to remove the staple as would tend to first break or cut the 25 wire, but by having a flat broad surface at the upper portion of the pointed end, this flat broad surface engages so much of the fence wire that it will not cut the wire, but instead will withdraw the staple.

30 After the tool is firmly inserted through the eye of the staple in the position shown in Figure 7, the operator need only move the handle end of the lever in a direction toward the post, so that the post forms a fulcrum for the lever and the staple is easily withdrawn.

By having the point provided with a straight upper face and a round lower face, as shown at 12 in Figure 2, the point may 40 readily be driven into the post, and when driven far enough to engage the wire, the handle end may be used as a lever for pulling the staple without danger of breaking off the pointed end. This round surface also 45 tends to prevent the point from penetrating too deeply into the post as it tends to guide the end out of the post and in such direction as to pull out the staple instead of penetrating the post.

50 I claim as my invention:

A staple puller especially designed for removing fence wires held to wooden posts by staples, said puller comprising in combination a straight handle portion formed oblong 55 in cross section, so that it may be firmly held against twisting movements in the operator's hand, and having one end designed to receive hammer blows, the other end of the body being formed with a tapered end portion, the 60 sides thereof being tapered from the body portion toward the point, and being also tapered from the under surface toward the upper surface, said under surface and said upper surface both being formed flat in cross 65 section, and the lower surface being formed

with a rounded portion near its end curved upwardly to meet the flat upper portion of the end portion, the said end portion being disposed at an angle relative to the body of approximately 32° so that an operator 70 may by striking hammer blows upon the other end of the body easily drive the tapered end into a post under a staple and fence wire.
